CONTROLLABLE REACTANCE

Robert W. Clark, Teaneck, N. J., and Frank J. Somers, New York, N. Y., assignors to Radio Corporation of America, a corporation of Delaware

Application April 30, 1943, Serial No. 485,119

6 Claims. (Cl. 179—171.5)

1

This application concerns reactance of the tube type and control means for controlling the size of the said reactance. In an application the reactance is in an oscillation generating circuit or in a tuned circuit wherein oscillatory energy flows. Means is provided to control the said reactance and thereby control the tuning of the generator circuit or tuned circuit to control the timing of the oscillatory energy in the generating circuit or tuned circuit.

An object of our invention is to improve the operation of reactance tube circuits of the type described above in general. A more specific object is to improve such systems when the oscillations generated or flowing in the tuned circuit are of large amplitude. The voltage fed to the reactance tube control grid in phase quadrature is derived from the cathode circuit of a cathode follower type stage. The amplitude of the voltage on the cathode circuit of the cathode follower type stage will be less than that on the grid and the voltage on the cathode circuit may be adjusted to the desired amount. Thus an improved means for regulating the quadrature voltage for best operation is provided.

Another object of the present invention is to reduce the effects of regeneration in the reactance tube, say for example, in case a reactance tube of the triode type is used. Since the grid of the reactance tube derives the quadrature voltage from the cathode impedance of a stage of the cathode follower type and the cathode to ground impedance of such a stage is generally of a low value, regeneration effects in the reactance tube are reduced.

In addition the modulation amplifier feeding into the grid of the reactance tube, which is also connected to the cathode impedance of the cathode follower stage, is feeding into a low impedance load and the system is particularly useful in case a wide band of modulation frequencies are used, such as, for example, video or similar signals.

In our system the control of the tube reactance may be in accordance with control potentials such as used in automatic frequency control systems or in accordance with modulating potentials of any type. It is especially useful where the modulating potentials extend over a wide range of frequencies. The controllable reactance may be used to control or modulate the phase or frequency or the phase and frequency of wave energy.

Throughout the specification and claims the term timing modulation will be used and is intended to cover the various types of phase and frequency modulation or modified forms thereof.

In describing our invention in detail reference will be made to the drawings wherein the single figure illustrates a tube and circuit arrangement wherein a controllable capacity is developed be-

tween the electrodes of the tube in a new and improved manner and used in a novel manner to control the timing of oscillatory energy.

In the drawings, 10 is an oscillation generator having its first and second grids and cathode regeneratively coupled in a tuned circuit comprising capacity C and inductance L. The mode of operation of this type generator is believed well known and a detailed statement thereof is believed unnecessary. The generator is, however, of the regenerative type and of the electron coupled type. In the generator the second grid acts as an anode, and the cathode is maintained above ground alternating current potential by the chocking inductance 12. The oscillation generating electrodes are coupled substantially by the electron stream only in the tube to the output circuit 14 coupled to the anode.

The tube 20 has its anode to cathode internal impedance in shunt to L and C and in this tube 20 the reactive effect is developed. The reactive effect is across the circuit LC and as a consequence determines the reactance thereof and the timing of the oscillations generated. LC may be a tuned circuit wherein an alternating current is induced rather than the tank of a generator. The high potential end of C and L and the anode 22 of tube 20 are coupled to the first grid 24 of an amplifier tube 26 so that the phase of the alternating current potential on the first grid 24 of tube 26 and on the anode 22 of tube 20 and on the high potential end of circuit LC is the same. The tube 26 is of the cathode follower type having in its cathode ground circuit a resistance potentiometer 30. A point on this resistance potentiometer is coupled by resistance 31 to the control grid 24 to provide the required grid bias in this tube. The amount of the voltage developed in the cathode circuit is determined by the resistance 30, type of tube 26, and the voltage on grid 24. The potential drop across the potentiometer 30 is supplied to a phase shifting network including resistance R and condenser C1. R1 is the grid resistor for tube 20 and normally is large in comparison with R and may be disregarded in considering the phase shifting network. However, where R1 is small it must be taken into account when considering the phase shifting network. The common terminals of resistance R and C1 are connected to the control grid 32 of tube 20. The resistor 34, shunted by radio and modulation frequency bypass condenser 36, provides the bias for the control grid of tube 20.

In my system, during operation the alternating current potential at the cathode end of resistance 30 varies in phase with the alternating current potential supplied to the grid 24 of tube 26, and in the arrangement this alternating current potential is of the same phase as the alternating current potential on the anode 22 of tube 20. The

resistance R and condenser C_1 provide a phase shifting network by means of which the alternating voltage fed to the grid 32 from the potentiometer resistance 30 is shifted about 90° in phase so that in the tube 20 we have a phase quadrature relation between the high frequency voltages on the anode 22 and grid 32. In other words, in this tube 20 the current to the anode is 90° out of phase with respect to the anode voltage and the tube instead of being an amplifier, simulates a reactive effect which is reflected into the tank circuit CL . If the current to the anode leads the anode voltage the reactive effect which is complex is essentially capacitive. If the current to the anode lags the anode voltage the complex reactance is essentially inductive.

In an arrangement shown R , C_1 and R_1 (R_1 is large and neglecting the capacity of cathode 37 to ground) are dimensioned so that the phase of the voltage on the grid 32 is in quadrature with the voltage on the anode 22. In the arrangement shown the resistance of R is made large as compared to the reactance of C_1 so that the current through the circuit is largely resistive and is in phase with the voltage. The reactance drop across the condenser C_1 is 90° out of phase with the current, i. e., lags the current by about 90° so that the voltage on the control grid 32 lags the voltage on the anode 22 by about 90° and the reactive effect is inductive. If R_1 is small so that the reactive drop across C_1 is not 90° out of phase (less than 90°) with the current in the condenser C_1 an inductance L_2 is added to the phase shifting network say in series with R or in series with R_1 . This inductance then retards the current and causes the current to lag the voltage an amount sufficient to bring the reactance drop across C_1 to about a phase quadrature relation with respect to the voltage at the cathode of tube 26.

The capacity to ground of cathode 37 may be of such value as to create an appreciable phase angle between the voltage on grid 24 and the voltage on cathode 37. This phase angle can be corrected by connecting an inductance in series or parallel with resistor 30. The value of this inductance is such that at the mean frequency of the generated oscillations it will resonate with the capacity to ground of cathode 37.

By modulating an electrode in tube 20 in accordance with control or modulating potentials the tube conductance is varied, thereby varying the size of the reactive effect and changing the tuning of the circuit CL . The controlling or modulating potentials may be applied to tube 20. In a particular application a video amplifier tube 40 has its output electrodes coupled by a video peaking choke L_X and loading resistance LR to the control grid 32 of tube 20. This connection includes a radio frequency blocking circuit in the form of an inductance L_y which with its distributed capacity is parallel tuned to the center frequency at which the oscillator tube or tuned circuit LC is operating.

Considerable advantage is derived from the use of my novel arrangement where it is desirable or necessary to use a triode tube reactance at 20 or where a relatively strong oscillation generator is used or oscillations of considerable amplitude are set up in tank LC .

Where a reactance tube of the triode type is used at 20 the anode 22 to grid 32 feed-back inherent in such tubes is minimized by the low impedance of the output circuit of tube 26.

The phase shifting network may have the posi-

tions of R and C_1 , reversed so the reactive effect across the circuit LC will be capacitive, or the network may be composed of a resistance and inductance instead of a resistance and capacitance.

The quadrature voltage on the grid 32 of tube 20 most favorable for its operation may be obtained by dimensioning the potentiometer 30. Thus if the oscillations in tank circuit LC are strong, tube 26 may be used as an electronic attenuator to produce the required voltage on grid 32.

We claim:

1. In a tube reactance of controllable reactive value, two terminals across which alternating voltages appear and across which a reactive effect is to be produced, a first tube having output electrodes including a cathode coupled to said terminals, said tube having a control electrode, a second tube having input electrodes coupled to

20 said terminals, said second tube having a cathode connected by an impedance to the cathode of said first tube, a phase shifting circuit coupling said impedance to the control electrode of said first tube, whereby a reactive effect is produced in said 25 first tube, and connections for controlling the conductance of said first tube to thereby control the produced reactive effect.

2. In a tube reactance of controllable reactive value, a tuned circuit wherein alternating cur-

30 rent flows and across which a controllable reactive effect is to be produced, a first tube having an anode and a cathode coupled in shunt to a part, at least, of said first circuit, said tube having a control electrode, a second tube having input 35 electrodes coupled to said first circuit, said second tube having a cathode connected by an impedance to the cathode of said first tube, a phase shifting circuit coupling said impedance to the input electrodes of said first tube, whereby a reactive effect is produced in said first tube and reflected in said circuit and connections for modulating the conductance of said first tube in accordance with control potentials to vary said reactive effect.

3. In a timing modulation system, a tuned cir-

50 cuit wherein alternating current flows and across which a variable reactive effect is to be produced, a first tube having output electrodes including a cathode coupled in shunt to a part, at least, of said circuit, said tube having a control electrode, a second tube having input electrodes coupled to said first circuit, said second tube having a cathode connected by an impedance to the cathode of said first tube, a phase shifting circuit coupling said impedance to the control electrode of said first tube, whereby a reactive effect is produced in said first tube and connections for modulating the conductance of said first tube in accordance with signals to control said reactive effect and thereby correspondingly modulate the timing of said alternating current.

4. In a timing modulation system, a tuned cir-

55 cuit wherein alternating current flows and across which a variable reactive effect is to be produced, a first tube, a control electrode having an anode and a cathode coupled in shunt to a part, at least, of said circuit, whereby alternating voltage of a first phase is set up on said anode, a sec- 60 ond tube having a control electrode coupled to the anode of said first tube, said second tube having a cathode, an impedance connecting said last named cathode to the cathode of said first tube, a phase shifting network circuit coupling said impedance to the control electrode of said first tube, whereby a voltage is set up on said last

named electrode which is about 90° displaced in phase relative to the phase of the voltage on the anode of said first tube and a reactive effect is produced in said first tube and added to said tuned circuit and connections for modulating the conductance of said first tube in accordance with signals to control said reactive effect and thereby correspondingly modulate the timing of said alternating current.

5. In a simulated controllable reactance, an electron discharge tube having an anode, a cathode and a control grid and means for applying alternating current voltages substantially in phase quadrature upon the anode and control grid of the tube and for varying the tube's gain by control potentials to produce a variable reactive effect between the electrodes of said tube comprising, an additional tube having an anode, a cathode and an electron flow control electrode, a coupling for applying said alternating current to said electron flow control electrode, an impedance coupling the cathode of said additional tube to ground, a source of potential connected with the anode of said additional tube, a phase shifting circuit coupling said impedance to the control grid of said first tube, said phase shifting circuit including between said impedance and the control grid of said first tube a second impedance and between the said control grid and cathode of said first tube a condenser, and means for controlling the transconductance of said first tube in accordance with control potentials.

6. In a wave frequency control system an electron discharge tube having an anode, a cathode and a control grid, a tuned circuit wherein alternating current the timing of which is to be controlled flows, means for applying alternating cur-

rent voltages from said tuned circuit substantially in phase quadrature on the anode and control grid and for varying the tube's gain by control potentials to produce a variable reactive effect between the electrodes of said tube to vary the reactance of the said tuned circuit and thereby the timing of said voltages comprising, an additional tube having an anode, a cathode and a control electrode, a coupling between the control electrode of said additional tube and said tuned circuit, an impedance coupling the cathode of said additional tube to ground, a source of potential connected with the anode of said additional tube, a phase shifting circuit coupling said impedance to the control grid of said first tube, said phase shifting circuit including between said impedance and said control grid of the first tube an inductance and a second impedance and between the control grid and cathode of said first tube a condenser, a source of video signals and an amplifier tube having input electrodes coupled to said source of video signals and having output electrodes coupled to a load and to the control grid of said first tube.
